[57] CLAIM

The ornamental design for a bowl or similar article, substantially as shown and described.

DESCRIPTION

FIG. 1 is an elevational view of a bowl or similar article showing my new design;
FIG. 2 is a top plan view thereof;
FIG. 3 is a bottom plan view thereof;
FIG. 4 is a sectional view taken along line 4—4 of FIG. 1;
FIG. 5 is an elevational view of a modification of my new design for a bowl or similar article;
FIG. 6 is a top plan view thereof on a reduced scale;
FIG. 7 is a bottom plan view thereof on a reduced scale;
FIG. 8 is a sectional view taken along line 8—8 of FIG. 5;
FIG. 9 is an elevational view of another modification of my new design for a bowl or similar article;
FIG. 10 is a top plan view thereof on a reduced scale;
FIG. 11 is a bottom plan view thereof on a reduced scale; and
FIG. 12 is a sectional view taken along line 12—12 of FIG. 9.
